(57) CLAIM

The ornamental design for pockets, as shown and described.

DESCRIPTION

FIG. 1 is an enlarged front elevational view of the pockets showing our new design;

FIG. 2 is back elevational view thereof;

FIG. 3 is a right side elevational view thereof; and,

FIG. 4 is a left side elevational view thereof.

The long dashes immediately adjacent to the solid-line portions of the design form the boundary of the design, with long dashes forming no part of the claimed design.

The short dashes on the surface of the pockets in the Figures represent stitching, which form no part of the claimed design. The long dashes in the drawings outlining the shorts represent a portion of the design, which form no part of the claimed design.
